UNITED STATES PATENT OFFICE

149,430

DESIGN FOR AN AUTOMOBILE BODY

Casimir S. Lupinski, Hamtramck, Mich.

Application February 15, 1947, Serial No. 136,931

Term of patent 14 years

(Cl. D14—3)

To all whom it may concern:

Be it known that I, Casimir S. Lupinski, a citizen of the United States and a resident of the city of Hamtramck, county of Wayne, and State of Michigan, have invented a new, original, and ornamental Design for an Automobile Body, of which the following is a specification, reference being had to the accompanying drawings, forming a part thereof, in which drawings,

Fig. 1 is a perspective view of my automobile body;

Fig. 2 is a side elevational view of said automobile body;

Fig. 3 is a front elevational view of said automobile body;

Fig. 4 is a rear elevational view thereof;

Fig. 5 is a sectional view on line 5—5 of Fig. 4;

Fig. 6 is a sectional view on line 6—6 of Fig. 4; The dotted line showing the wheels is for illustrative purposes only.

I claim:

The ornamental design for an automobile body, as shown, and described.

CASIMIR S. LUPINSKI.
